UNITED STATES PATENT OFFICE

ALBERT CHARLES BARTLETT, OF WATFORD, ENGLAND, ASSIGNOR TO THE GENERAL ELECTRIC COMPANY LIMITED, OF LONDON, ENGLAND

LINE BALANCE FOR LOADED TELEPHONE CIRCUITS

Application filed March 30, 1925, Serial No. 19,421, and in Great Britain April 4, 1924.

This invention relates to line balances for loaded telephone circuits. The problem of making satisfactory line balances is that of devising some comparatively simple and cheap combination of impedance elements which shall have at all telephonic frequencies an impedance nearly the same as the sending end impedance of the actual line.

10 The object of the invention is to provide improved line balances the impedance of which can be made to simulate closely over the range of telephonic frequencies the impedance of a loaded cable which is terminated at half loading coil or over a considerable range of fractional coil terminations.

In the accompanying drawing, Fig. 1 illustrates one form of the invention and Fig. 2 illustrates a modification.

20 A line balance according to the present invention consists of a new arrangement of elements having inductance, capacity, and resistance, the values of which may be determined in terms of the constants of the line to be balanced, as hereinafter more fully described.

Although the line balance described in this specification, is primarily a mid-coil termination balance yet it can be adapted to balance the cable over a considerable range of fractional coil terminations.

Let the impedance of a loaded cable terminated at a half loading coil be considered and let:

35 Z =Impedance of an infinite periodically loaded line starting from the middle point of a loading coil.

n =Frequency of the current in the line.

H =Inductance of each of the loading coils.

40 l =Distance between loading coils.

C =Capacity per unit length of line.

L =Inductance per unit length of line.

R =Resistance per unit length of line.

$p=2\pi n$.

45 $j=\sqrt{-1}$.

Then if the inductance of the line apart from the loading coils be negligible, it is known that the impedance of an infinite line starting from the middle point of a loading coil is given approximately by

$$Z=\sqrt{\frac{H}{Cl}-\frac{H^2p^2}{4}-\frac{jR}{pC}} \quad (1)$$

In practice both $\frac{H^2p^2}{4}$ and $\frac{R}{pC}$ are always less than $\frac{H}{Cl}$. Hence

$$Z=\sqrt{\frac{H}{Cl}-\frac{H^2p^2}{4}-\frac{1}{2}\cdot\frac{jR}{pC}\cdot\frac{1}{\sqrt{\frac{H}{Cl}}}} \quad (2)$$

The imaginary term on the right of Equation (2) represents a condensive reactance of a series condenser of capacity $k=\frac{2C}{R}\sqrt{\frac{H}{Cl}}$ therefore, one element of the line balance will be a series condenser of this capacity.

The problem therefore reduces to determining a network that has a resistance decreasing with frequency according to the above relation and of zero reactance.

I have found that the network shown in Figure 1, by choosing suitable values of the elements, can be made to give this required result; the values of the elements being definitely related to the electrical constants of the line.

The values of the elements are determined in the following way.

The impedance of the network of Fig. 1 is given by

$$Z^1=jpL_1+\frac{1}{jpK+\frac{1}{r+jpL_2}} \quad (3)$$

$$Z^1=jpL_1+\frac{jp[L_2(1-p^2KL_2)-Kr^2]}{(1-p^2L_2K)^2+p^2K^2r^2}+\frac{r}{(1-p^2L_2K)^2+p^2K^2r^2} \quad (4)$$

The real part of Z^1 , i. e. the resistance component of the impedance of this network is

$$\frac{r}{1+p^2(K^2r^2-2KL_2)+p^4K^2L_2^2} \quad (5)$$

5 which is of the form

$$\frac{r}{1+ap^2+bp^4} \quad (6)$$

The resistance component of the cable impedance from Equation (2) is seen to be

$$\sqrt{\frac{H}{Cl}} \cdot \sqrt{1-\frac{p^2HCl}{4}}$$

which is of the form $B\sqrt{1-Ap^2}$ (7)

15 By making $r=B$ and choosing K and L_2 of suitable values these expressions (6) and (7) can be made to have very nearly equal values over a large range of values of p .

Already we have $r=B$ so that the expressions are equal at zero frequency, and further we can make the two expressions have equal values at two other frequencies. These frequencies should be near the middle and near the upper limit of the band of speech frequencies, i. e. about 7000 and 12000 radians per second.

20 The procedure is first to determine the values of $\sqrt{1-Ap^2}$ near the two frequencies mentioned above. For example for a medium loaded cable the values of $\sqrt{1-Ap^2}$ are about 0.9 and 0.6.

30 The problem then is to make $\frac{1}{1+ap^2+bp^4}$ and $\sqrt{1-Ap^2}$ have the values .9 and .6 at the same frequencies. For the frequency at which $\sqrt{1-Ap^2}$ has the value .9

$$\begin{aligned} 1-Ap^2 &= .81 \\ Ap^2 &= .19 \\ p^2 &= \frac{.19}{A} \\ &\hline \end{aligned}$$

40 Thus we must have

$$\begin{aligned} 45 \quad \frac{1}{1+\frac{.19}{A}+b\left(\frac{.19}{A}\right)^2} &= 0.9 \\ 1 &= \frac{1}{0.9} + \frac{.19}{A} + b\left(\frac{.19}{A}\right)^2 \\ 50 \quad 1 &= 0.9 + \frac{.171a}{A} + \frac{0.0325b}{A^2} \end{aligned}$$

and for the other value in a similar way

$$1 = 0.6 + \frac{.384a}{A} + \frac{0.246b}{A^2}$$

55 Solving these equations for a and b $b = A^2 \times 1.01$ and $a = A \times 3.96$

Thus $K^2r^2 - 2KL_2 = .396A$

$$K^2L_2^2 = 1.01A^2$$

Thus $KL_2 = A$ (approximately)

$$K^2r^2 = 2.396A$$

$$L_2 = .645B\sqrt{A}$$

$$K = \frac{1.55\sqrt{A}}{B}$$

65 $r = B$

Thus L_2 , K and r are now all determined in terms of constants of the cable.

The reactance of the network of Fig. 1 is from (4)

$$pL_1 + \frac{p[L_2(1-p^2KL_2)-Kr^2]}{(1-p^2KL_2)^2+p^2K^2r^2}$$

Substituting values from above in the second term of this expression, the term becomes

$$\frac{-p\{0.905r\sqrt{A}+0.645rA^{3/2}p^2\}}{1+0.4p^2A+p^4A^2}$$

In practice this is approximately equal

$$to -0.905 p \cdot r \cdot \sqrt{A}$$

and therefore represents a negative inductance.

Accordingly, if we make $L_1 = .905r\sqrt{A}$ the reactance of the network of Fig. 1 will be zero and we shall have a network, which, over the useful telephonic range, gives a non-reactive resistance decreasing with frequency in the desired manner. To complete the balance a series condenser k will be required of

90 the value $\frac{2C}{R}\sqrt{\frac{H}{Cl}}$. The balance thus consists of the arrangement of elements as shown in Figure 2, the value of each element being determined by constants of the cable in accordance with the following table.

$$L_1 = 0.45H$$

$$k = \frac{2C}{R}\sqrt{\frac{H}{Cl}}$$

$$L_2 = 0.32H$$

$$K = 0.77Cl$$

$$r = \sqrt{\frac{H}{Cl}}$$

100 In practice it may be found that the balance can be improved by altering the values a few per cent from those calculated.

110 By altering the value of L_1 , obviously, the balance can be made to correspond with a termination at any point in the loading coil from full termination to $(.5 - .45) = .05$ termination; in the latter case of course $L_1 = 0$.

I claim:

1. A line balance, the impedance of which over the range of telephonic frequencies simulates closely the sending end impedance of a periodically loaded cable terminated at half loading coil, the said balance comprising elements including a capacity, an inductance, a second inductance, and a resistance, all arranged in series, and a second capacity connected in parallel with the second inductance and the resistance, the values of the several elements being determined in terms of the constants of the line to be balanced, substantially as described.

120 2. A line balance, the impedance of which over the range of telephonic frequencies simulates closely the sending end impedance of

a periodically loaded cable terminated at a fractional coil termination, the said balance comprising elements including a capacity, an inductance adjusted to the desired fractional loading coil termination, a second inductance, and a resistance, all arranged in series, and a second capacity connected in parallel with the second inductance and the resistance, the values of the several elements first being determined in terms of the constants of the line to be balanced, substantially as described.

3. A line balance, the impedance of which over the range of telephonic frequencies simulates closely the sending end impedance of a periodically loaded cable terminated at a small fractional loading coil termination, comprising elements including a capacity, an inductance adjusted to a value corresponding with the desired fractional loading coil termination, said value being included within a range of values having zero as one limit thereof, a second inductance, and a resistance all arranged in series, and a second capacity connected in parallel with the inductance and the resistance, the values of the several elements being determined in terms of the constants of the line to be balanced, substantially as described.

4. An artificial line for simulating the sending end impedance of a periodically loaded cable terminated at half loading coil the said line comprising elements including a capacity, an inductance, a second inductance, and a resistance all arranged in series, a second capacity connected in parallel with the second inductance and the resistance, the elements of the artificial line being so proportioned that the resistance component of the sending end impedance of the said periodically loaded cable and the resistance component of the impedance of the artificial line are approximately equal, and the reactance component of the sending end impedance of the said periodically loaded cable, and the reactance component of the impedance of the said artificial line are approximately equal.

5. An artificial line for simulating the sending end impedance of a periodically loaded cable terminated at fractional loading coil termination the said line comprising elements including a capacity, an inductance adjusted to the desired fractional loading coil termination, a second inductance, and a non-inductive resistance all arranged in series, and a second capacity connected in parallel with the second inductance and the non-inductive resistance, the elements being so proportioned that within the limits of the band of speech frequencies the real component of the sending end impedance of the said cable and the real component of the impedance of the said line are approximately equal, and the imaginary component of the sending end impedance of said cable and the imaginary com-

ponent of the impedance of said line are approximately equal.

6. A line balance for simulating the sending end impedance of a periodically loaded cable terminated at small fractional loading coil termination, comprising elements including a capacity, an inductance adjusted for the desired fractional loading coil termination within a range of values having .05 and .5 as limiting values, a second inductance, and a resistance all arranged in series, and a second capacity connected in parallel with the inductance and the resistance, the elements of the line balance being so proportioned that within the limits of the band of speech frequencies, the resistance components of the sending end impedance of the cable and of the line balance are approximately equal, and reactance components of the sending end impedance of the cable and of the line balance are approximately equal.

In testimony whereof I affix my signature.
ALBERT CHARLES BARTLETT.
